UNITED STATES PATENT OFFICE.

ARTHUR W. WALKER, OF MALDEN, MASSACHUSETTS.

DRAFT-REGULATOR.

1,106,904.

Specification of Letters Patent.

Patented Aug. 11, 1914.

Application filed October 18, 1912. Serial No. 726,417.

To all whom it may concern:

Be it known that I, ARTHUR W. WALKER, a citizen of the United States, residing at Malden, in the county of Middlesex and

5 State of Massachusetts, have invented new and useful Improvements in Draft-Regulators, of which the following is a specification.

This invention relates to improvements in draft regulators.

10 More particularly it relates to regulators for controlling the combustion in a furnace of any sort, for example, the furnace in a stove or range, or in the heating plant of a building, whether operating through the medium of hot air, steam, or hot water.

Such furnaces as now constructed commonly have an ash pit under the grate, provided with a door for removal of ashes, the door having a "draft" slide for admission 20 of air directly to the grate. They also have a duct leading from the fire-box to the chimney flue, to discharge smoke and gaseous products of combustion. For controlling the rate of combustion a "check draft" is 25 sometimes provided, admitting more or less air directly to the flue, thus diminishing the capacity or suction of the flue for products of combustion.

It is an important feature of the present 30 invention that these three elements, inflow of air to the grate to support combustion, outflow of products of combustion, and inflow of air directly to the flue for checking its suction may all be controlled directly by 35 a single moving part or adjustment.

Another feature is that the invention provides means for controlling definitely the amount of air having access to the grate to support combustion, and permits the ash-pit 40 door to be eliminated if desired, or made air tight.

There are also other features and advantages incidental to the invention, which will appear from the disclosure herein made.

45 In the accompanying drawings: Figure 1 is a side elevation of a furnace, of a type used for heating a residence; Fig. 2 is a perspective view of a detail, enlarged, showing a form modified in one respect; and Figs. 3, 4 and 5 are side elevations in medial vertical section, on the larger scale, showing in detail the regulator of Fig. 1 or Fig. 2 in three different positions.

In the drawings, which represent one 55 manner of applying the invention to a "hot air" furnace of a type now in extensive use

for heating residences and buildings, 10 represents the fire-box of the furnace, 11 the grate, 12 the ash-pit under it and 13 the door to the ash-pit.

14 is the discharge duct from the fire-box, and 15 the pipe sometimes known as the "smoke pipe" that receives the discharge and conducts it to the chimney flue, this pipe being herein for brevity called the "flue." 60 It will be understood that the products of combustion may pass either directly or indirectly from the fire-box to the discharge 14 according to any suitable or desired arrangement of passage within the heater, and also 65 that the door 13 of the ash-pit may have the usual "draft" slide for admitting air, though this is made unnecessary by the present invention, the air to support combustion being introduced and controlled by the novel 70 means now to be described.

16 is an inlet for fresh air arranged adjacent to the discharge pipe 14 from the fire-box, and to the air entrance to flue 15 and also adjacent to the entrance to a duct 17, 80 herein called the "draft" duct, by which air to support combustion is conducted to the grate. As illustrated, this inlet 16 is placed at the level of the dome or top of the fire-box, on the back side of the apparatus, where 85 the pipe for the discharge of smoke and gases from the fire-box issues from the apparatus and joins the flue; and the draft duct is a pipe leading thence downward on the back side and into the apparatus terminating in the ash-pit 12. But this might be arranged differently if desired, and the draft duct may, for example, be within the casing, or formed within the castings, or may be otherwise arranged, as by going within the 90 combustion chamber and downward through the grate to the ash-pit. Air entering at 16 may also go upward into the flue 15 to check the draft on the furnace.

The numeral 18 indicates a damper which, 100 in the form illustrated in the drawing, is hinged on a pivot pin 19, and can control all four passages, viz, from the smoke discharge to the flue, from the air inlet to the flue, the air inlet alone, and the opening from the 105 air inlet to the draft duct. To do this it is capable of being set in the various positions illustrated in Figs. 3, 4 and 5, and in various intermediate positions. The damper has a lower wing or yane 18' adapted to close, or 110 open to varying degrees, the entrance to the draft duct 17; an upper vane 18" adapted

to switch the flue 15 either to a connection with air inlet 16, or with the smoke discharge 14, or to both, in an intermediate degree; and a vane 18", which may be conveniently formed as a terminal plate at the end of the vane 18", adapted to close the inlet 16. The box 21 which contains the damper is shaped with a suitable opening in which the vane 18" may swing to and fro between the extreme positions seen in Figs. 5 and 3, and has its interior wall curved at 21' where the end of vane 18" slips upward past it from the position of Fig. 3 to that of Fig. 4, so that this movement does not open the "check draft" connection from inlet 16 to the flue, although it does diminish the opening of draft duct 17. The plate 18" which closes the inlet 16 when in its extreme downward position, is set so that its lower surface retreats gradually toward the center, from the line traveled by the tip of the vane 18". As a consequence it is not necessary that the lower end of this plate get past the wall 21' before air can enter the flue, but an opening is formed as soon as its leading edge, which is the tip of vane 18, passes, gradually increasing with further movement toward the position of Fig. 5. The surface 21 is generated as a portion of a cylinder concentric with the pivot 19 about which the vane 18" swings; and the face of the plate 18" may be of any design which produces the desired increase of opening from 16 into 15. While this increase is occurring, draft duct 17 and also the discharge pipe 14 are being gradually closed. A handle 20 may be arranged outside of the chamber or box 21 in which the damper is set, to control its position; and this handle may in turn be controlled either manually or automatically. Thus, in Fig. 1, the presence of a thermostatic or other type of controller is indicated by a wire 22, which may be assumed to descend as the temperature increases, letting the weight 20' draw the handle and thus turn the damper around to the left toward the position of Fig. 5. If automatic control be not used, any suitable means may be employed for maintaining the damper fixed in its desired position, such as the friction incidental to the parts, or a simple rack 23 pivoted to the handle and resting on a pin 24 as indicated in Fig. 2.

In the usual operation of a furnace embodying the invention, all the air which is to support combustion enters through the draft duct 17, thus enabling the usual ash-pit door to be omitted, or, if not, to be made air tight, and enabling perfect control of the amount of air. Movement of handle 20 diminishes the size of the discharge opening for the products of combustion; and at the same time makes this diminution of discharge opening effective by diminishing correspond-

ingly the pull of the chimney flue, by admitting air thereto. As the same movement of handle 20 diminishes the size of draft duct, the combustion is reduced more effectually than if it remained open, in which case the power that the fire itself has to create a draft might continue the combustion for some time on a larger scale than desired.

Hitherto the adjustment of the openings through the ash-pit door for the admission of air has had to be made according to the judgment of the person charged with the care of the furnace. Housekeepers, and particularly their servants are rarely skilled as combustion engineers. The slide draft for admitting air is frequently shut too much to permit getting the full power of the furnace when that is wanted, or open too much to get combustion at an economical rate, when that is wanted. There is no way to measure the area openings, cracks, etc., that let air through the ash-pit door, even if one knew precisely what area of opening is desirable. It is in fact customary for householders to set the slide draft, smoke damper and check draft independently of each other, making considerable changes with one, without changing the others.

The present invention, by the construction described or suitable modifications of it, enables the various dampers in the passages for controlling combustion to be designed by competent combustion engineers when the furnace is built, with the opening which each shall have for each setting of the other dampers carefully and definitely predetermined.

The unskilled housekeeper or servant then, by a single motion of the damper handle 20 not only controls all of the combustion passages, but sets them in proper relation to each other with the skill of a combustion engineer.

The illustrated arrangement of the passages, by which they all radiate from one location, enables all the various dampers to be condensed into a single moving part. This provides simplicity of construction and of operation. It also makes possible the advantages illustrated in Fig. 3, which shows the position the parts may occupy when coal is being added or ashes removed. The terminal vane 18" closes the inlet 16 completely, thus shutting both the draft duct of the grate and the check draft of the flue, while leaving the flue 15 wide open for drawing gases, fine dust, etc., from the fire-box into the flue. This position is attained by swinging the handle 20 as far as it will go to the right; and it will be observed that in the automatic control arrangement of Fig. 1 the damper arm can under these circumstances slide freely up on the rod 22; and may be held in the extreme position as long as desired by a spring catch 20".

The part 21' is shown hinged, for access to the interior for cleaning out soot. Any soot that may fall past the edges of damper 18 from the flue above will descend through the 5 steep slope of the air draft duct to the ash-pit. While the vane 18' is represented as a plane wing it will be understood that it may be made of any suitable shape that will produce a change in size of opening, corresponding properly to the changes in openings 10 to the flue 15 that result as the vane 18' is moved. And in general it may be said that changes in many respects may be made from the precise structure here illustrated without departing from the scope of the invention.

I claim as my invention:—

1. A draft regulator for furnaces comprising the combination of a duct for draft of air to the under side of the grate; a duct from 20 the upper side of the grate to the chimney flue, these ducts passing adjacent to each other; and a unitary damper comprising a movable direct continuation of the wall of each duct, located where the ducts are adjacent to each other, regulating both and preventing interchange of gases between them.

2. A draft regulator for furnaces comprising the combination of separate ducts for 30 indraft of air and outdraft of products of combustion, passing in proximity to each other, and an L-shaped regulating damper having a vane projection into each duct.

3. A draft regulator for furnaces comprising the combination, with a duct for draft of 35 air to the grate, a duct from the grate to the chimney and an air inlet adapted to be connected to each duct, of a damper having interconnected vanes, one regulating the duct to the grate, another the duct to the chimney, and a third the air inlet, the whole arranged and adapted to open the passage from 40 grate to the chimney progressively as the air draft to the grate opens, closing the air inlet connection to the chimney duct progressively 45 during the first part of the motion and closing the air inlet during the latter part of the motion.

4. A draft regulator for furnaces comprising a box, containing passages through 50 which air goes in to the grate and the products of combustion go out to the chimney, combined with a damper pivoted within the box at the corner between the said two passages, separating the said two passages so as 55 to prevent interflow of gases and regulating them simultaneously and similarly.

5. A draft regulator for furnaces comprising a box having an outlet downward 60 for draft of air to the grate; an inlet on one side receiving discharge from the furnace; an inlet on the opposite side receiving air; and an outlet upward to the chimney; combined with a damper pivoted between the 65 first mentioned outlet and first mentioned inlet, comprising one vane apportioning the

chimney connection between the inlets while the said vane is in an upper portion of its swing, closing the connection of chimney to air inlet while in a lower portion of its swing, and another vane gradually opening 70 the outlet to the grate as the first mentioned vane swings downward.

6. A draft regulator for furnaces comprising a box having an outlet downward for draft of air to the grate; an inlet on one 75 side receiving discharge from the furnace; an inlet on the opposite side receiving air; and an outlet upward to the chimney; combined with a damper pivoted between the first mentioned outlet and first mentioned inlet; comprising one vane apportioning the chimney connection between the inlets while the said vane is in an upper portion of its swing; closing the connection of chimney to air inlet while in a lower portion of its swing, and another vane gradually opening 80 the outlet to the grate as the first mentioned vane swings downward; and a third vane having a surface depending and gradually bearing inward from the tip of the first 85 mentioned vane, whereby the rate of change of air inlet connection to the chimney is moderated.

7. A draft regulator for furnaces comprising a box having an outlet downward 90 for draft of air to the grate; an inlet on one side receiving discharge from the furnace; an inlet on the opposite side receiving air; and an outlet upward to the chimney; combined with a damper pivoted between the first mentioned outlet and first mentioned inlet; comprising one vane apportioning the chimney connection between the inlets while the said vane is in an upper portion of its swing; closing the connection of chimney to air inlet while in a lower portion of its swing, and another vane gradually opening 95 the outlet to the grate as the first mentioned vane swings downward; and a third vane having a surface depending and gradually bearing inward from the tip of the first 100 mentioned vane, whereby the rate of change of air inlet connection to the chimney is moderated, the depending vane being adapted to close said air inlet at its extreme swing, 105 while the discharge is wide open to chimney and the said vane controlling the outlet to grate is wide open.

8. A draft regulator for furnaces comprising a box having an inlet for air and 110 outlets for the air entering through said inlet leading respectively to the grate and to the chimney, and an inlet from the grate; combined with a damper pivoted within the box and having means to substantially close 115 one of said inlets at each end of its movement and in intermediate positions to govern the flow of air through the two outlets.

9. A draft regulator for furnaces comprising a box having an inlet for air and 120

4
outlets for the air entering through said inlet leading respectively to the grate and to the chimney, and an inlet from the grate; combined with a damper pivoted within the box and having means to substantially close the air inlet at one end of its movement and at the other end of its movement to substantially close the outlet to the grate and the inlet from the grate, and in its intermediate positions to vary the capacity of

said outlet to the grate increasing it simultaneously with increase of capacity of the inlet from the grate and with decrease of the inlet to the chimney flue.

Signed by me at Boston, Mass., this sixteenth day of October, 1912.

ARTHUR W. WALKER.
